UNITED STATES PATENT OFFICE.

CORTLAND W. DAVIS, OF OAK PARK, ILLINOIS, ASSIGNOR TO THE MANTLE LAMP COMPANY OF AMERICA, OF CHICAGO, ILLINOIS, A CORPORATION OF ILLINOIS.

HARP FIXTURE FOR LAMPS.

Application filed January 27, 1922. Serial No. 532,255.

To all whom it may concern:

Be it known that I, CORTLAND W. DAVIS, a citizen of the United States, residing at Oak Park, in the county of Cook and State 5 of Illinois, have invented certain new and useful Improvements in Harp Fixtures for Lamps, of which the following is a specification.

The invention relates to harps such as 10 are employed for pendently supporting lamps and lamp shades, objects thereof being to produce a harp which is so constructed as to simplify the construction of the component parts, to render the assembling 15 of the parts easy for unskilled labor, and to secure compactness in packing for shipment, whereby the users of lamp-supporting devices may be able to secure harps of convenient construction at a minimum 20 cost.

The lamp harp of my invention contains pieces of metal made according to pre-determined designs of such character that they 25 may be readily set up by the user and united by the use of screws or other simple devices without the exercise of more mechanical skill than is possessed by the ordinary individual. The several parts are stamped or 30 otherwise fashioned into final shape at the factory, and are ready for the assembling operation by the user without alteration.

The harp includes a top bracket, side bars having at their upper ends holes into which malleable lugs of the bracket extend, a shade-supporting ring secured to the side bars by bolts and carrying clips and screws for retaining a shade fixedly in position, and a lamp-supporting ring attached by bolts to the lower ends of said side bars 40 for receiving the bowl of a lamp. These rings are recessed to receive the side bars, and both the rings and the side bars are made from flat stock metal which requires no machining.

45 The invention will be best understood if reference is made to the accompanying drawing in which—

Figure 1 is a perspective view of the completed harp, and

50 Figure 2 is a view showing the top bracket and parts of the side bars of the harp in vertical section.

The side bars 1 are made from pieces of ordinary flat metal, bent, as shown, not only to fit the lamp and shade rings which

are of different sizes, but to afford room for the bowl of a lamp and also give to the harp a pleasing ornamental design.

The bracket 2 is made of flat malleable metal, and is provided with a hole 3 for the reception of a sustaining hook and with lugs 4 extending through holes 5 in the inwardly bent upper ends 6 of the side bars 1, the extremities of these lugs being upset to insure a secure union of the parts. 60

The lamp ring 7 is made adjustable for convenience in inserting a lamp bowl, but the means of adjustment constitutes no part of the present invention. This ring is bent at diametrically opposite sides to form inner 70 recesses or seats for the lower ends of the side bars 1, screw bolts 9 extending through coinciding holes in the ring and the side bars being used to fixedly unite these elements. 75

The shade ring 10 is bent to form diametrically disposed external recesses 11 for the reception of the side bars 1, and the union of the parts is effected by screw bolts 12 extending through coinciding holes 80 in the ring and the side bars. Clips 13 and screws 14, constituting no part of this invention, are attached to the shade ring for the purpose of supporting and locking a shade in position on the harp. 85

The shade ring 10, with the external recesses 11 and the clips 13, provides a support for a lamp shade of a diameter large enough to mount a shade large enough to pass down over the outwardly-bent sections 90 of the upper end of the side bars 1 to the shade support. The lamp ring 7 with the inner recesses 8 allows the attachment of the side bars 1 without interference with the support of a circular lamp bowl from the 95 upper edge of the lamp ring 7.

From the foregoing it will be seen that the several parts of my harp are, with the exception of the bracket 2, made from common flat metal strips which have merely 100 been bent to the required shapes and perforated at suitable points for the reception of the respective retaining devices, and that the bracket is of simple character requiring no particular skill in its production since 105 it may be stamped in a usual manner. When the harp fixture is packed ready for transportation to the consumer, it will be seen that it may be assembled in a package of relatively small dimensions as the shade 110

ring 10 and the lamp ring 7 are separable complete entities that may be laid flat with the side bars. The assembling of the fixture is easily accomplished by the consumer with the aid of a screw driver only.

Having thus described my invention, what I claim is:

1. A harp fixture including side bars, a shade band having open external recesses disposed between and receiving said side bars, and a lamp band having open internal recesses receiving the lower portion of said harp.
2. A harp fixture including side bars, an externally recessed shade band disposed between said bars and an internally recessed band encircling the lower portion of said harp, said rods of said harp being adapted to substantially fit said recesses and means for retaining said side rods in the recesses of said bands.

3. A harp fixture including converging side bars, a shade band sustained between the narrowed part of said fixture, and a lamp band carried by and encircling the lower portion of said fixture and of greater diameter than said shade band, said shade band being adapted to support a shade from the inside of said shade. 25

4. A harp for lamps including a cut-metal sustaining bracket having lugs, flat metal side bars provided with holes for receiving said lugs, and an internally recessed lamp ring having the lower ends of said side bars fitting its recesses. 30

In testimony whereof I hereby affix my signature in the presence of two witnesses.

CORTLAND W. DAVIS.
